US0D1041620S

(12) **United States Design Patent** (10) **Patent No.:** **US D1,041,620 S**
(45) **Date of Patent:** **** Sep. 10, 2024**

(54) **FAUCET**

(71) Applicant: **Wenzhou Furuisi Building Materials Co., Ltd**, Wenzhou (CN)

(72) Inventor: **Chunhe Qiu**, Wenzhou (CN)

(73) Assignee: **Wenzhou Furuisi Building Materials Co., Ltd**, Wenzhou (CN)

(**) Term: **15 Years**

(21) Appl. No.: **29/933,858**

(22) Filed: **Mar. 22, 2024**

(30) **Foreign Application Priority Data**

Mar. 19, 2024 (CN) 202430142216.6

(51) **LOC (14) Cl.** **23-01**

(57) **CLAIM**

The ornamental design for a faucet, as shown and described.

DESCRIPTION

FIG. 1 is a front perspective view of a faucet in accordance with my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the faucet that form no part of the claimed design.

1 Claim, 8 Drawing Sheets
